U.S. Appl. No. 29/703,774, filed Aug. 29, 2019, Hangartner et al.

Primary Examiner — Philip S Hyder(74) *Attorney, Agent, or Firm* — Reinhart Boerner Van Deuren s.c.

(57)

CLAIM

We claim the ornamental design for a utility knife, as shown and described.

DESCRIPTION

FIG. 1 is a top, right perspective view of a utility knife, embodying the new design.

FIG. 2 is a front view of the utility knife of FIG. 1.

FIG. 3 is a rear view of the utility knife of FIG. 1.

FIG. 4 is a right view of the utility knife of FIG. 1.

FIG. 5 is a left view of the utility knife of FIG. 1.

FIG. 6 is a top view of the utility knife of FIG. 1.

FIG. 7 is a bottom view of the utility knife of FIG. 1.

FIG. 8 is a top, right perspective view of the utility knife of FIGS. 1 through 7, depicted using a wire frame drawing technique.

FIG. 9 is a front view of the utility knife of FIG. 8.

FIG. 10 is a rear view of the utility knife of FIG. 8.

FIG. 11 is a right view of the utility knife of FIG. 8.

FIG. 12 is a left view of the utility knife of FIG. 8.

FIG. 13 is a top view of the utility knife of FIG. 8.

FIG. 14 is a bottom view of the utility knife of FIG. 8.

FIG. 15 is a top, right perspective view of a second embodiment of the utility knife;

FIG. 16 is a front view of the utility knife of FIG. 15.

FIG. 17 is a rear view of the utility knife of FIG. 15.

FIG. 18 is a right view of the utility knife of FIG. 15.

FIG. 19 is a left view of the utility knife of FIG. 15.

FIG. 20 is a top view of the utility knife of FIG. 15.

FIG. 21 is a bottom view of the utility knife of FIG. 15.

FIG. 22 is a top, right perspective view of the utility knife of FIGS. 15 through 21, depicted using a wire frame drawing technique;

FIG. 23 is a front view of the utility knife of FIG. 22.

FIG. 24 is a rear view of the utility knife of FIG. 22.

FIG. 25 is a right view of the utility knife of FIG. 22.

FIG. 26 is a left view of the utility knife of FIG. 22.

FIG. 27 is a top view of the utility knife of FIG. 22; and,

FIG. 28 is a bottom view of the utility knife of FIG. 22.
